DESIGN FOR A COMBINED BREAD AND PASTRY CABINET

Daniel E. Barnes, Riley, Kans.

Application August 28, 1942, Serial No. 108,061

Term of patent 14 years

To all whom it may concern:

Be it known that I, Daniel E. Barnes, a citizen of the United States of America, residing at Riley, county of Riley and State of Kansas, have invented a new, original, and ornamental Design for a Combined Bread and Pastry Cabinet, of which the following is a specification, reference being had to the accompanying drawing, forming a part thereof, wherein: bread and pastry cabinet, showing my new design in opened position.

I claim:

The ornamental design for a combined bread and pastry cabinet, as shown.

DANIEL E. BARNES.
